UNITED STATES PATENT OFFICE.

FRITZ DÖHLE, OF LEIPZIG, GERMANY, ASSIGNOR TO ADOLF BLEICHERT & COMPANY
OF LEIPZIG-GOHLIS, GERMANY.

CARRIAGE FOR ROPEWAYS AND THE LIKE.

1,073,410.

Specification of Letters Patent. Patented Sept. 16, 1913.

Application filed May 10, 1912. Serial No. 696,346.

To all whom it may concern:

Be it known that I, FRITZ DÖHLE, residing at Leipzig, Germany, citizen of the German Empire, have invented new and useful Improvements in and Relating to Carriages for Ropeways and the Like, of which the following is a full, clear, and exact description of my invention.

On the four-wheeled ropeway carriages hitherto employed, consisting of two single carriages, the carrying beam suspending the load is supported by the single carriages and is either arranged over the running rollers or hung from a rigidly fitted, horizontal pivot in the center of the single carriages. The former arrangement necessitates a considerably higher construction of the carriage with a consequent lengthening of the connection rails in the ropeway stations and entails a considerable increase in the cost of the supporting structural parts. In the latter case the vertical rotary pivots must be either arranged outside the carrying rope axis, thus making the adaptation of the carriages for negotiating curves more difficult, or, the frame of the hanger must be bent toward the center of the carriages over the rail and hung under the carriage frame, an arrangement which also entails a comparatively high construction and increased cost. In the present invention these drawbacks are avoided by fitting horizontal pivots on the carrying beam suspending the load, which extend transversely over the rails or carrying rope and, around which the single carriages can move vertically, whereas the vertical pivots which allow the adaptation of the carriages for the curves are quite or very nearly in the center line of the carriages, which they connect with the horizontal pivots. An example of the construction of the invention is shown in the accompanying drawings, in which—

Figure 1 shows in elevation the improved carriage and a portion of the carrying rope. Fig. 2 is a transverse section taken on the line A—B, Fig. 1.

Similar characters of reference designate corresponding parts throughout the several views.

The carrying beam *b* is fixed laterally below the carriage *a* and carries at both ends a horizontal carrying pivot *c* which rests pivotally in the bearing bush *d*, whereby a vertical rotation of the single carriage be-

comes possible. The bearing bushes *d* carry vertically one above the other the lower supporting pivots *e* and the upper bearing pivots *f*, which are themselves pivotally arranged in the lower supporting bearings *g* 60 and the upper bearings *h*. The bearing bushes *d* with the pivots *e* and *f* are fitted between the two running rollers *i* at the level of the running roller axle, and, for the purpose of allowing the centrally horizontal 65 movement of the single carriages *a*, in the interior of the carriage body and above the center of the carrying rope.

Having now particularly described and ascertained the nature of my said invention 70 and in what manner the same is to be performed, I declare that what I claim is:

1. In a double carriage for ropeways, consisting of two single carriages with two wheels each and a beam connecting these 75 carriages and situated at the side thereof, horizontal pivots extending from the ends of the said supporting beams above and transversely to the rail, and vertical pivots near the center plane of the rail and connecting the said horizontal pivots with the respective bodies of the single carriages.

2. In a double carriage for ropeways, consisting of two single carriages with two 85 wheels each and a beam connecting these carriages and situated at the side thereof, horizontal pivots extending from the ends of the supporting beams above and transversely to the rail and through the side shield of the carriage, and vertical pivots 90 near the center plane of the rail and connecting the horizontal pivots with the respective bodies of the single carriages.

3. In a double carriage for ropeways consisting of two single carriages with two 95 wheels each and a beam connecting these carriages and situated at the side thereof, horizontal pivots extending from the ends of the supporting beams above and transversely to the rail in about the same height, 100 as the axles of the wheels and through the side shield of the carriage, and vertical pivots near the center plane of the rail and connecting the horizontal pivots with the respective bodies of the single carriages.

4. In a double carriage for ropeways consisting of two single carriages with two 105 wheels each and a beam connecting these carriages and situated at the side thereof, horizontal pivots extending from the ends 110

of the supporting beams above and transversely to the rail and through the side shield of the carriage, and vertical pivots near the center plane of the rail and connecting the horizontal pivots with the respective bodies of the single carriages, and supporting bearings in the lower part of

the carriages to transmit the load on said horizontal pivots to the carriage bodies.

FRITZ DÖHLE.
